TOY SLEIGH

Monroe J. Singer, Hialeah, Fla., assignor to Nu-Seal Inc.,
New York, N.Y., a corporation of New York

Application October 29, 1957, Serial No. 48,271

Term of patent 14 years

(Cl. D34—15)

Fig. 1 is a side perspective view of a toy sleigh showing my new design;

Fig. 2 is a front elevational view thereof; and

Fig. 3 is an enlarged view of a fragment of the ornamentation running along the top edges of the body of the sleigh.

The side not shown is the same in appearance as the side shown and the back is substantially plain.

I claim:

The ornamental design for a toy sleigh, substantially as shown and described.
